HAIR DRYER

Edward J. Petrick, Park Ridge, Ill., assignor to Breford Manufacturing, Inc., Schiller Park, Ill., a corporation of Illinois

Filed May 26, 1964, Ser. No. 80,158

Term of patent 14 years

(Cl. D86—10)

The side of the stand not shown is the mirror image of the side shown.

The dominant features of the design are shown in full line in the drawing.

I claim:

The ornamental design for a hair dryer, as shown and described.
